FOLDING HIGH CHAIR

Frederick W. Schroeder, Strasburg, Ill.

Application January 30, 1953, Serial No. 334,139

7 Claims. (Cl. 155—127)

1

This invention relates to a folding high chair, and more particularly, has reference to a chair of this type characterized by its adaptability for collapse into the form of a relatively small and thin box capable of being carried like a brief case or traveling bag.

Summarized briefly, the invention includes a back plate, and arms, a seat, and a base all hinged to and collapsible against the back plate. Brace means are provided that are themselves collapsible against the arms and base respectively, said brace means being separably connectible to the seat so as to hold the seat, arms, and base in an extended position when the high chair is to be used. A removable tray and back rest are supported by the arms and seat respectively, when the chair is in use. On movement of the several parts to a collapsed position, the back plate and base, together with top and bottom strips carried by the back plate, coact to confine all the remaining parts of the assembly, thus forming said assembly into a thin, box-like container, which container is equipped with a carrying handle.

The desirability of a high chair collapsible into a light, compact, and readily portable box-like shape will be well appreciated to those parents whose living quarters are decidedly cramped, or who are required to travel frequently with small children.

Obviously, persons whose living conditions are affected in this manner are generally unable to make use of a conventional high chair, which is ordinarily bulky. The main object of the present invention can, accordingly, be stated as being the provision of a high chair which, when collapsed, will take up a minimum of area and will be readily portable, but which, when extended for use, will define a comfortable chair having a seat, back, and tray area approximating those of an ordinary, conventionally designed high chair.

Another object of importance is to provide a high chair as stated which, while possessing the desirable characteristics noted above, will nevertheless be rugged, so as to withstand hard and long usage.

Another object of importance is to provide a foldable high chair as stated in which the movement of the parts to extended and collapsed positions respectively can be accomplished with ease and speed.

Still another object is to provide a high chair as stated which, though possessing the several desirable characteristics noted above, can yet be

2

manufactured in quantity production at relatively low cost.

Other objects will appear from the following description, the claims appended thereto, and from the annexed drawings, in which like reference characters designate like parts throughout the several views, and wherein:

Figure 1 is a perspective view of the high chair as it appears when unfolded and ready for use;

Figure 2 is a perspective view showing the high chair folded into the form of a small carrying case;

Figure 3 is a front elevational view of the high chair unfolded;

Figure 4 is a longitudinal sectional view on line 4—4 of Figure 3;

Figure 5 is a transverse sectional view on line 5—5 of Figure 4;

Figure 6 is a greatly enlarged, detail sectional view on line 6—6 of Figure 4, showing a separable connection between the brace means and seat;

Figure 7 is a sectional view on line 7—7 of Figure 6;

Figure 8 is a sectional view, on an enlarged scale, taken substantially on line 8—8 of Figure 4 and showing the details of the connection of the tray to the arms;

Figure 9 is a side elevational view of the high chair, as it appears while being folded; and

Figure 10 is an enlarged sectional view, portions being broken away, taken on line 10—10 of Figure 2.

Referring to the drawings in detail, the high chair constituting the present invention includes a back plate designated generally by the reference numeral 11. The back plate itself comprises a number of connected parts, the main part being a plate member 12. The plate member 12 is formed from a relatively thin, flat piece of material of rectangular outer configuration, and could be fashioned from plywood or any other material having the requisite characteristics of strength and lightness.

The plate member 12 has a pair of guide rails 14 secured to its opposite longitudinal edges. The guide rails 14 extend for substantially the full height of the plate member 12, and as shown in Figure 5, have inner longitudinally extending recesses 16 of right angled cross sectional shape, thereby to provide a slideway on the front surface of the plate member.

A bottom strip 18 is also included as a part of the back plate 11, and extends the length of the bottom edge of the plate member 12, said

bottom strip 18 being fixedly secured in any suitable manner to the plate member, and projecting forwardly and horizontally therefrom.

The back plate also includes a top strip 19, which is hingedly connected to the top edge of the plate member 12, in a manner to be discussed in detail hereinafter.

When the high chair is folded as shown in Figures 2 and 10, the plate member 12 will form one side of a carrying case, while the relatively narrow bottom and top strips 18, 19 will provide the bottom and top portions of said case.

Receiving and fixedly connected to the lower ends of the guide rails 14 are lower support brackets 20. Each of these is of L-shape. Upper support brackets 22 are formed similarly to the brackets 20, but are disposed oppositely to the brackets 20, as best shown in Figure 1.

Hinge support plate 24, formed as flat, relatively small bars, are pivotally connected at one end, as at 26, to the inner walls of the lower support brackets 20, said hinge support plates 24 projecting forwardly beyond the front edge of the bottom strip 18, and being pivotally connected, at their projecting ends by hinge pins 28 to angular hinge brackets 30.

A base 32 is formed from a flat, rectangular piece of material, and is substantially coextensive in length and width with the plate member 12. The purpose of so dimensioning the base 32 is to cause the base to coact with the plate member 12, in forming the opposite sides of the carrying case when the high chair is folded (see Figure 2).

The hinge brackets 30 are fixedly connected in any suitable manner to the inner or upper surface of the base 32, at a location spaced a short distance from the back edge of the base. As a result, the base 32 can appropriately be considered as being hinged to the bottom end of the back plate 11, for swinging movement between one position (shown in Figure 1) in which the base projects forwardly and horizontally from the back plate, and a second position (shown in Figure 10) in which the base 32 is collapsed against the back plate 11. It will be understood, in this connection, that the back plate is considered as including not only the plate member 12, but also the top strip 19 and bottom strip 18, against which the base 32 abuts in the collapsed position of said base.

It may be noted that the hinge connection of the base to the back plate is a double hinge connection, the base pivoting about the points 26 and 28 during the swinging movement of said base between its respective extreme positions.

Secured fixedly to the upper surface of the base 32, and spaced inwardly from the free or front edge of the base, are angular hinge brackets 34, said brackets 34 including triangular wear plates 36 having inturned lips that will engage the beveled lower ends of a pair of lower braces 38. The lower braces 38 are pivotally connected, at said lower ends thereof, to the respective brackets 34 and wear plates 36, and in the extended position of the base 32, the lower braces extend upwardly from the base, said lower braces being inclined from the vertical in the direction of the back plate 11 as best shown in Figure 1 and in Figure 4.

Upper braces have been designated by the reference numerals 40, and cooperate with the lower braces 38 in holding a seat 42 in a forwardly extended position. As will be described in detail hereinafter, the upper braces 40 are pivotally connected

connected to the arms of the high chair, but it is important, at this point in the description, to note only the manner in which the braces 38, 40 are connected to the seat 42.

This connection is shown in detail in Figures 6 and 7, and as will be noted, at opposite sides of the seat 42, at the free or front edge of the seat, there are mounted C-shaped latch plates or keepers 44, said latch plates being secured to the seat 42 by means of screws 46 or equivalent fastening elements. Each latch plate straddles its associated side edge of the seat 42.

Each keeper or latch plate 44 has its bight portion spaced outwardly a short distance from the adjacent side edge of the seat 42, and slidably engaged between said bight portion and adjacent side edge is a latch key 48 having oppositely extended lips on its respective ends forming finger grips, whereby the key can be shifted back and forth in its associated keeper, to the right and left in Figure 6.

Each key 48 has a button hole slot 50, and extending through said slot is a connecting pin 52 the inner end of which is adapted to extend into a recess 53 formed in the adjacent side edge of seat 42 and registering with the button hole slot.

Intermediate its ends, the pin 52 has diametrically opposite grooves 54 (see Figure 7). It will be noted, in this regard, that when the key 48 is shifted to the left in Figures 6 and 7, the large end of the button hole slot will be so located as to permit extraction of the pin 52. When, on the other hand, the key 48 is shifted to the right in Figures 6 and 7, the opposite edges of the narrow end of the button hole slot will engage in the groove 54 of the pin, and will lock the pin against withdrawal.

It thus becomes apparent that when, as shown in the drawings, the pin 52 extends through registering openings formed in the overlapping ends of the braces 38, 40 respectively, and is locked to the seat 42, said connecting pin will represent a separable connection between the braces and seat that holds the several parts against movement to collapsed position.

To opposite sides of the seat 42, at the back edge thereof, there are connected channeled hinge plates 56, each of said plates straddling its associated side edge of the seat 42 and being pinned to said seat. Projecting outwardly from the bight portion of each plate 56 is a stud 58, said stud extending into a complementary recess formed in the adjacent guide rail 14, thus to provide a hinged connection between the seat 42 and the back plate 11.

The location of a hinge axis of the seat 42, said hinge axis being defined by the studs 58, is such as will cause the rear edge portion of the seat 42 to extend into the path of slidably movement of a back rest 60, when the seat 42 extends forwardly from the back plate. This construction is best shown in Figure 4, wherein it will be seen that the back rest 60 is formed from a flat piece of approximately rectangular material, so dimensioned as to thickness as to permit the same to be slidably mounted for up and down movement in the recesses 16 of the guide rail. Thus, when the back rest 60 is slidably shifted in one direction, it will project above the back plate 11, and subsequent movement of the seat 42 to extended position relative to the back plate will cause the seat 42 to form a stop that will retain the back rest in its upper position. When, subsequently, the seat 42 is collapsed, it will no

longer extend in the path of slidable movement of the back rest 60, and the back rest can be slidably adjusted downwardly from the position thereof shown in Figure 4, to a location at which it is substantially in registration with the plate member 12.

At its upper end, the back rest 60 can be formed with an opening, to afford convenience in gripping the back rest 60 when said back rest is to be adjusted between its respective positions.

A pair of arms is included in the high chair, said arms being designated by the reference numeral 62 and being pivotally connected, at their inner or rear ends, to the upper support brackets 22 of the back plate 11. The arms 62, at a location spaced well inwardly from the outer or free ends thereof, have pivotal connections 64 to the upper ends of the upper braces 40. The upper braces 40 are thus connected to the arms 62 in such a manner as to cause said upper braces to either depend from the arms in the manner shown in Figure 4, or be collapsed against the arms, in longitudinal contact therewith, when the arms themselves are to be collapsed against the back plate.

A tray has been designated by the reference numeral 66, and can be formed from a rectangular piece of material having a recessed top surface. The opposite side edge portions of the tray 66 rest upon the respective arms 62, and are detachably connected to the arms 62 in selected positions of adjustment. The selected positions of adjustment are such as to permit the tray 66 to be adjusted either toward or away from the back rest 60, depending upon the size of the child to be accommodated in the high chair.

The nature of the connection of the tray to the arms 62 is best shown in Figure 8, and as will be noted, secured to the underside of the tray 66, adjacent each side edge thereof, is a relatively elongated, shallow slide housing 68. The slide housing 68 can be formed from a single piece of metal material, having a low, upwardly extending peripheral flange abutting against the underside of the tray 66, said housing being secured permanently to the tray by screws 69 or their equivalents.

Spaced longitudinally of the slide housing 68 are openings 70, said openings being spaced equal distances apart for substantially the full length of the housing.

At one side of the housing, intermediate the opposite ends thereof, I provide a longitudinal slot 72. A slide 74 from a flat length of bar material, is slidably reciprocable within the housing 68, and is formed, throughout its length, with a longitudinal series of uniformly spaced button hole slots 76. A laterally projecting handle 78 is integrally provided upon one side edge of the slide 74, and projects through the slot 72 of housing 68. The opposite ends of slot 72 limit movement of the handle, and hence the slide 74, in opposite direction within the housing.

A flat plate 89 is fixedly secured to the upper surface of each arm 62, and has an upwardly projecting stud or latch pin 82. The pin 82 is formed with opposed grooves (Figure 8), in which are engageable the opposite side edges of the narrow portions of the button slots 76.

It will be seen that the tray 66 can be located any desired distance from the back rest 60. When the tray 66 has been located at its proper distance from the back rest, the pin 82 will project through one of the several openings 70. Subsequently, movement of the handle 78 in the

direction of the arrows shown in Figure 8, will be effective to shift the slide 74 to a position in which one of the button hole slots 76 will be shifted to a location at which the opposite edges of its narrow end will lock in the grooves of the pin.

Spaced transversely of the top edge of the plate member 12 are hinges 84, said hinges being connected to the top strip 19. Thus, the top strip 19 can swing between one position shown in Figure 4, in which position it is coplanar with and projects upwardly from the plate member 12, and a second position shown in Figure 10. In its second position the top strip forms the top wall of a carrying case. A carrying handle 88 is attached to the top strip, and a pin 90, on the outer or free end of base 32, engages in an opening provided in a locking strap 92, that is attached to the top strip 19, for the purpose of holding the several parts against movement from their collapsed position.

In use, and assuming that the high chair has been unfolded, said high chair can be positioned upon a conventional chair, not shown, and will have a tray, seat, and back rest portion approximating in size the corresponding parts of a conventional high chair. Subsequently, when the high chair is to be folded, the pins 52 will first be disengaged from the braces 38, 40. It may be noted that the pins 52 will not be accidentally lost when so disengaged, since the key 48 can be returned to its locked position for the purpose of holding the pins in their associated keepers.

In any event, when this step in the folding operation has been accomplished, the seat 42 can be swung upwardly in the direction of the arrow shown in Figure 9, and the arms 62 can be swung downwardly. Base 32 is also swung upwardly, the lower braces 38 collapsing against the base while the upper braces collapse against their associated arms 62. The double hinge connection of the base to the back plate permits the base to move into registration with the plate member 12 in the collapsed condition of the parts.

The tray 66 will, of course, previously have been detached from the arms 62, and can be inserted in the space between the plate member 12 and base 32, as shown in Figure 10. Similarly, collapsing of the seat permits the back rest 60 to move to its lower position.

After the parts have been completely collapsed, a flat, box-like carrying case will result, which can be readily carried and stored in a small area. In a full size device, such a case is 12 x 16 x 2 inches in size, and its compactness will thus be readily appreciated.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A foldable chair comprising: an upstanding back plate; arms, a base, and a seat all hinged to the back plate to swing between a first position in which they project forwardly from the

back plate and a second position in which they are collapsed thereagainst; a pair of upper braces hinged to the arms to swing between a first position in which they depend from the arms and a second position in which they are collapsed against the arms; a pair of lower braces hinged to the base to swing between a first position in which they extend upwardly from the base and a second position in which they are collapsed thereagainst; and means separably connecting the upper braces, lower braces, and seat in the first positions thereof.

2. A foldable chair comprising: an upstanding back plate; arms, a base, and a seat all hinged to the back plate to swing between a first position in which they project forwardly and horizontally from the back plate and a second position in which they are collapsed thereagainst, the seat being connected to the back plate at a location between the connections of the base and arms thereto; a pair of upper braces hinged to the arms to swing between a first position in which they depend from the arms and a second position in which they are collapsed against the arms; a pair of lower braces hinged to the base to swing between a first position in which they extend upwardly from the base and a second position in which they are collapsed thereagainst; and means separably connecting the upper braces, lower braces, and seat in the first positions thereof.

3. A foldable chair comprising: an upstanding back plate; arms, a base, and a seat all hinged thereto to swing between a first position in which they project forwardly and horizontally from the back plate and a second position in which they are collapsed thereagainst, the seat being connected to the back plate at a location between the connections of the base and arms thereto, said back plate and base being formed as flat members substantially coextensive with each other in height and width; a pair of upper braces hinged to the arms to swing between a first position in which they depend from the arms and a second position in which they are collapsed against the arms; a pair of lower braces hinged to the base to swing between a first position in which they extend upwardly therefrom and a second position in which they are collapsed thereagainst; means separably connecting the upper braces, lower braces, and seat in the first positions thereof, the arms, seat, and braces all being disposed between the back plate and base in the collapsed condition of the parts, to form the back plate and base into a container therefor; and a carrying handle on the back plate.

4. A foldable chair comprising: a back plate including an upstanding plate member and a bottom strip secured to and projecting forwardly from said plate member; arms, a base, and a seat all hinged to the plate member to swing between a first position in which they project forwardly and horizontally from the plate member and a second position in which they are collapsed thereagainst, the seat being connected to the plate member at a location between the connections of the base and the arms thereto, said plate member and base being flat and substantially coextensive with each other in height and width; a pair of upper braces hinged to the arms to swing between a first position in which they depend from the arms and a second position in which they are collapsed against the arms; a pair of lower braces hinged to the base to swing between a first position in which they extend upwardly therefrom and a second position in which they are collapsed thereagainst; means separably connecting the upper braces, lower braces, and seat in the first positions thereof, the arms, seat, and braces all being disposed between the plate member and the base in the collapsed condition of the parts, to form the plate member and base into opposite sides of a container therefor, said bottom strip forming the bottom of said container; a carrying handle on the upper end of the plate member; a back rest slidably mounted on the back plate to extend the same upwardly in said first position of the arms, base, and seat; and a tray removably

wardly therefrom and a second position in which they are collapsed thereagainst; means separably connecting the upper braces, lower braces, and seat in the first positions thereof, the arms, seat, and braces all being disposed between the plate member and the base in the collapsed condition of the parts, to form the plate member and base into opposite sides of a container therefor, said bottom strip forming the bottom of said container; and a carrying handle on the upper end of the plate member.

5. A foldable chair comprising: a back plate including an upstanding plate member and a bottom strip secured to and projecting forwardly from said plate member; arms, a base, and a seat all hinged to the plate member to swing between a first position in which they project forwardly and horizontally from the plate member and a second position in which they are collapsed thereagainst, the seat being connected to the plate member at a location between the connections of the base and the arms thereto, said plate member and base being flat and substantially coextensive with each other in height and width; a pair of upper braces hinged to the arms to swing between a first position in which they depend from the arms and a second position in which they are collapsed against the arms; a pair of lower braces hinged to the base to swing between a first position in which they extend upwardly therefrom and a second position in which they are collapsed thereagainst; means separably connecting the upper braces, lower braces, and seat in the first positions thereof, the arms, seat, and braces all being disposed between the plate member and the base in the collapsed condition of the parts, to form the plate member and base into opposite sides of a container therefor, said bottom strip forming the bottom of said container; a carrying handle on the upper end of the plate member; and a back rest slidably mounted on the back plate to extend the same upwardly in said first position of the arms, base, and seat.

6. A foldable chair comprising: a back plate including an upstanding plate member and a bottom strip secured to and projecting forwardly from said plate member; arms, a base, and a seat all hinged to the plate member to swing between a first position in which they project forwardly and horizontally from the plate member and a second position in which they are collapsed thereagainst, the seat being connected to the plate member at a location between the connections of the base and the arms thereto, said plate member and base being flat and substantially coextensive with each other in height and width; a pair of upper braces hinged to the arms to swing between a first position in which they depend from the arms and a second position in which they are collapsed against the arms; a pair of lower braces hinged to the base to swing between a first position in which they extend upwardly therefrom and a second position in which they are collapsed thereagainst; means separably connecting the upper braces, lower braces, and seat in the first positions thereof, the arms, seat, and braces all being disposed between the plate member and the base in the collapsed condition of the parts, to form the plate member and base into opposite sides of a container therefor, said bottom strip forming the bottom of said container; a carrying handle on the upper end of the plate member; a back rest slidably mounted on the back plate to extend the same upwardly in said first position of the arms, base, and seat; and a tray removably

connected to and extending between the arms in said first position of the arms.

7. A foldable chair comprising: a back plate including an upstanding plate member and a bottom strip secured to and projecting forwardly from said plate member; arms, a base, and a seat all hinged to the plate member to swing between a first position in which they project forwardly and horizontally from the plate member and a second position in which they are collapsed thereagainst, the seat being connected to the plate member at a location between the connections of the base and the arms thereto, said plate member and base being flat and substantially coextensive to each other in height and width; a pair of upper braces hinged to the arms to swing between a first position in which they depend from the arms and a second position in which they are collapsed against the arms; a pair of lower braces hinged to the base to swing between a first position in which they extend upwardly therefrom and a second position in which they are collapsed thereagainst; means separably connecting the upper braces, lower braces, and seat in the first positions thereof, the arms, seat, and braces all being disposed between the plate member and the base in the collapsed condition of the parts, to form the plate member and base into opposite sides of a container therefor, said bottom strip forming the

bottom of said container; a carrying handle on the upper end of the plate member; and a back rest slidably mounted on the back plate for movement between opposite extreme positions in one of which said back rest projects above the back plate to extend the same upwardly, and in the other of which the back rest is retracted into substantial registration with the plate member of the back plate, said seat, in the first position thereof, extending into the path of slidable movement of the back rest to provide a stop limiting movement of the back rest to the second named extreme position thereof.
